CLUTCH FOR POWER WINCHES

Edward B. Yoncoski, Buffalo, N. Y.

Application November 28, 1947, Serial No. 788,445

3 Claims. (Cl. 192—76)

1

This invention relates generally to winches, more particularly to improvements and refinements in the construction of power winches of the type adapted to be mounted on a deck or floor, connected to a motor, and operated by two levers controlling a clutch connected with the reel of the winch and a brake respectively.

A primary object of this invention is to provide a winch which is particularly well adapted for use by small building contractors, farmers, and in small mines, boats, and the like.

Another important object of this invention, ancillary to the foregoing object, is to provide a winch which is adapted to be constructed in light weight and easily portable form, and in which the clutch mechanism and braking mechanism, as well as all other parts of the winch, are mounted on a single frame to facilitate transportation of the winch from one position to another, it being understood that the winch will be rigidly secured to the floor or deck while being operated.

Still another object of this invention is to provide braking means for a winch, in which uniform movement of the brake control handle causes a non-uniform movement of the means directly applying braking pressure, thus facilitating smoother arresting of the reel of the winch when the brakes are applied.

Still another object of this invention is to provide improved means for equalizing the action of the different brake shoes used in the device.

Another object is to provide improved means for the adjustable setting of the different brake shoes.

And a last object to be specifically mentioned is to provide a power winch which is relatively inexpensive, completely practicable to manufacture, simple and convenient as well as safe to use, and which will give generally efficient and durable service.

With these objects definitely in view, together with other objects of a specific character and inherent in the construction of the device which will become apparent as this description proceeds, this invention resides in certain novel features of construction, combination and arrangement of parts and portions as will be described in the specification, particularly pointed out in the appended claims, and illustrated in the accompanying drawings which form a material part of this application, and in which:

Figure 1 is a longitudinal vertical sectional view of the assembled winch, the figure being taken substantially on a center line of the device.

2

Figure 2 is a transverse vertical sectional view, taken on the line 2—2 in Figure 1;

Figure 3 is an end view in elevation;

Figure 4 is a fragmentary side elevational view of one end of the machine, the view being designed to show a construction of the brake mechanism;

Figure 5 is an enlarged detail view of the main portions of the means used to secure the ends of the brake band;

Figure 6 is a transverse sectional view illustrating further the structure shown in Figure 5 and how the same is mounted on the frame, the major portion of the figure being in side elevation;

Figure 7 is a horizontal sectional view, fragmentary in character, and taken on the line 7—7 in Figure 6;

Figure 8 is a side elevational view of one of the clutch shoes;

Figure 9 is a group view showing the adjustable link means associated with the clutch shoe;

Figure 10 is an end view of the collar slidably associated with the drive shaft of the winch and the clutch mechanism;

Figure 11 is an elevational view of this same collar; and,

Figure 12 is a fragmentary enlarged detail view, taken on the line 12—12 in Figure 2.

Similar characters of reference designate similar or identical parts and portions throughout the specification and throughout the several views of the drawings.

Referring now to the drawings in detail, this winch includes a frame having a gear case 10 at one end, an upright 12 at the other end and a pair of preferably hollow connecting members 14 which are terminally welded to the gear case 10 and rigidly secured to the upright 12 by suitable bushings 16 welded to the said upright and taper pins 20 inserted through these bushings and the corresponding ends of the members 14. This construction allows the easy removal of the upright 12 for purposes of assembly of the machine, as well as for repair and replacement of certain parts of the machine when required.

The gear case is provided with suitable bearings for the shafts 22, 24 and 26, the first shaft 22 having rigidly secured thereto a drive pulley 28 adapted to receive a belt for connection to the power means associated with the winch. This same shaft carries a small gear wheel 30 which is in constant mesh with a larger gear wheel 32 rigidly secured to the shaft 24. The same shaft 24 carries another smaller gear 34 which

is in continuous engagement with the largest gear wheel 36 mounted on the one end of the shaft 26. This shaft 26 may be considered the drive shaft of the winch and it will be understood that the gears mentioned immediately above comprise a set of reduction gears enabling the employment of an electric motor as a power means.

The other end of the drive shaft 26 is journaled, as indicated at 38 in the central upper portion of the upright 12 and has freely mounted thereon, as by roller bearings 40, the reel 42 having an end plate 44 on the end adjacent the gear box 10 and a drum 46 rigidly secured to the other end thereof.

A clutch lever 48 is pivoted to a bracket 50 carried on the upright 12, the lower end of the lever 48 being bifurcated to straddle a collar 52 having a groove to receive a pair of roller bearings 54 carried by the bifurcated portion 56 of the lever. The said groove is indicated at 60 in Figure 11. It will be noted that the collar 52, being slidably mounted on the drive shaft 26, extends inwardly to abut the outer face of the clutch plate 62. This clutch plate 62 is a circular disc and is rigidly mounted upon a bushing 64 which is, in turn, rigidly secured by any suitable means to the drive shaft 26. The clutch plate carries a plurality, the drawings representing four, of clutch shoes which are generally represented by the numeral 66. Each clutch shoe is comprised of an arcuate plate 68 carrying a lining 70, a reinforcing plate 72, transverse reinforcing ribs 74 and 76, and a shank portion 78 of strap form and recessed as at 80. The shank portion 78 of the clutch shoes is slidably associated with a plurality of V-shaped guides 82 which are bolted, as at 84 to the clutch plate 62, the guides being grooved, as at 86, to receive edge portions of the shanks 78. It will be noted that each of the inner sides of the guides 82 is grooved as at 86 and that four of these guides serve to slidably mount the four clutch shoes 66. A plurality of coil springs 88 are secured under tension and in pairs between the clutch shoes 66 and certain of the bolts 84, in order to bias the clutch shoes into retracted or non-operative position.

The sliding collar 52 is provided with an annular shoulder 90 on the outside thereof and this annular shoulder is received in a groove 92 longitudinally disposed in a bearing member 94, which bearing member is best represented in Figure 9. The bearing 94 has an elongated curved surface which is received in the groove 96 of a fitting 98 having a shank 100 which is threadedly received in a block 102. It will be noted that this block is provided with squared sides 104 to receive a wrench and a nut 106 is used as a lock nut. The other end of the block 102 is provided with a reduced shank 108 which is received in the recess 110 of a shoe 112, while a strap spring 114 is interposed between the said other end of the block 102 and the flat surface 116 of the shoe 112, being retained against rotation by a pin 118 depending from the said flat surface and received in an aperture 120 in the flat spring. The opposite side of the shoe 112 is formed with an elongated curved recess 122 which receives a bearing 124, similar to the bearing 94 and having a groove 126 to receive a portion of the shank 78 within the recess 80.

The above described construction will provide for adjustability of the links which are comprised of the various elements numbered 94 to 124, and

it will be clear that while movement of the clutch handle 48 will force the clutch shoes 66 outwardly against the inner surface of the drum 46, this same construction will allow the different clutch shoes to seat properly upon the drum. In this connection it should be carefully noted that the collar 52 rotates with the drive shaft 26 and that the annular shoulder 90 of the collar is notched, as indicated at 128 in Figure 10, to assure rotation of the composite links described immediately above. The reel 42 is driven by the drum 46, and the clutch shoes 66, driven by the guides 82 bolted on the clutch plate 62, operatively connect the clutch plate and shaft 26 with the drum, when the shoes 66 are expanded as a result of the shifting of the collar 52 by the clutch handle 48.

The braking mechanism includes a brake lever 130, pivoted as at 132 on the upright 12 and having a conventional complement of a finger-grip control 134, link rod 135 and pawl 136 engageable with a toothed rack 138 fixed on the upright 12. This rack may be formed integral with a plate 140 which is bolted on the upright 12 and on one of the members 14 of the frame. A guide rail 142 having lateral flanges is bolted, as at 143, to the plate 140 and a slide 144 is mounted for vertical sliding movement on this rail, the slide having a vertical slot to receive said rail and this slot being bridged by a bar 145 at the lower end of the slide. A link 146 is terminally and pivotally connected to a lower portion of the lever 130 and to an extending portion of the slide 144 apertured as at 148, while the upper end of the slide is provided with a transversely bored terminal 149 which is connected, by means of the pin 150, with the reinforced end 152 of a strap brake band 154 which encircles the drum 46 in frictional engagement therewith and which has its other end adjustably secured to a lower portion of the plate 140, by means of a bolt 156 which is secured to the other end of the brake band 154 and which is inserted through the aperture 158 of the plate 140 and adjustably held in place by the nut 160.

The operation of this invention will be clearly understood from the foregoing description of the mechanical details thereof, taken in connection with the above recitation of the objects sought to be achieved by this invention. It will be clear that all of the objects are amply attained by this invention and that the operation thereof will entail no special procedure. In recapitulation, it may be added that equalization of the braking action by the different clutch shoes 66 is accomplished by the flat springs 114. The springs 114 tend to overcome the effect of unequal wear in the clutch shoe linings 70 and any inaccuracy in the manual adjustment of the linkages.

Many minor variations may be made in the structural details and proportionment of the various parts of this invention, all within the spirit and scope thereof, and it should be understood that the drawings and specification are illustrative rather than limiting and that the invention should be considered as limited only by a proper interpretation of the terminology used in the subjoined claims.

Having described the invention, what is claimed as new is:

1. In a power winch including a reel freely rotatably mounted on a driven shaft and having a drum at one end, a clutch plate having guides thereon and carried by said driven shaft and disposed within said drum, clutch shoes slidably

mounted on said guides, means to force said shoes outwardly into contact with said drum comprising a collar longitudinally slidable on said shaft, an annular shoulder on said collar, bearing members having elongated curved surfaced portions and grooves to receive the shoulder, members having grooves to receive said curved surfaced portions and having threaded shanks, blocks adjustably mounted on the shanks, shoes pivotally mounted on the blocks, said last-named shoes having grooves opposite said blocks, elongated bearings received in the last-mentioned grooves and engaging said clutch shoes and means to bias said clutch shoes into retracted positions.

2. A device according to claim 1, and wherein said clutch shoes include shank portions, and said elongated bearings having longitudinally disposed slots to engage said shank portions upon an elongated contact surface centrally of the shank portions.

3. A device according to claim 1, and includ-

ing a strap spring compressed between said blocks and the shoes pivotally connected on the blocks to make the connection between said clutch shoes and said collar slightly resilient.
